UNITED STATES PATENT OFFICE.

JOHN MOORE AND RICHARD THORNTON, OF MOUNTAIN IRON, MINNESOTA.

EXPANSION-COMPENSATING RAILWAY.

1,178,745.

Specification of Letters Patent.

Patented Apr. 11, 1916.

Application filed May 6, 1915. Serial No. 26,353.

To all whom it may concern:

Be it known that we, JOHN MOORE and RICHARD THORNTON, citizens of the United States, residing at Mountain Iron, in the county of St. Louis and State of Minnesota, have invented certain new and useful Improvements in Expansion - Compensating Railways; and we do declare the following to be a full, clear, and exact description of the invention, such as will enable others skilled in the art to which it appertains to make and use the same.

Our invention relates broadly to improvements in the construction of railways and more particularly to compensating means for the expansion and contraction of the rails thereof.

Heretofore, numerous types of rail joints have been provided so constructed as to allow the ends of the rails to slide to a certain extent therein in order to allow said rails to expand and contract under changes in temperature. Numerous experiments along this line, however, have not revealed expansion and contraction compensating means which will positively perform the functions for which it is designed, it having been found that all of the devices heretofore manufactured and tested for this purpose, possess certain features which render them either totally or partially ineffective, with the result that most railways are now built in substantially the same manner as they were constructed years ago.

It is therefore the object of our invention to positively overcome the difficulties by simple and inexpensive construction.

To this end, the invention resides in certain novel features of construction and in the unique combination of parts hereinafter fully described and claimed and shown in the accompanying drawing wherein like reference characters designate corresponding parts throughout the several views and wherein:

Figure 1 is a longitudinal section of a portion of a railway constructed in accordance with our invention; Fig. 2 is a top plan view of the parts seen in Fig. 1, the positions which the rails assume when expanded, in dotted lines; and Fig. 3 is a vertical transverse section as seen on the plane indicated by the line 3-3 of Fig. 2. Fig. 4 is a diagram of a railway constructed in accordance with our invention.

In this drawing which constitutes a part

of the application, the numeral 1 designates a railway rail which is provided with a rectilinear inner side, while its outer side is beveled as seen at 2 from its intermediate portion to vanishing thicknesses at its ends, the rail 1 being of substantially the length of the other rails of the track.

Having their body portions alining with the central portion of the rail 1, are the two longitudinally alined and spaced rails 3, the inner sides of the adjacent ends of these rails 3 being sprung outwardly and disposed in sliding contact with the beveled portions 2 of said rail 1. By this means, when the rails 3 and the additional rails to which the same are connected by the usual fish plates or the like, expand or contract, the adjacent ends of said rails 3 merely slide toward or away from each other upon the beveled portions 2 of the rail 1, it being therefore evident that expansion caused by high temperatures, will not buckle the rails, while contraction thereof will have no tendency to snap the bolts at the joints or to break the fish plates.

It becomes expedient however, to provide simple and efficient means whereby the inner sides of the rails 1 and 3 are at all times maintained in strict alinement. For this purpose, a plurality of rail chairs 4 are provided, said chairs being secured by spikes or the like 5 to the cross ties 6. The chairs 4 include horizontal base plates 7 through which the spikes 5 pass, said plates being provided with longitudinally alined depressions 7^a of the width and depth of the bases of the rails 3. It is within the alined depressions 7^a that said rails 3 are slidably positioned, with the innermost base flanges 95 thereof disposed flush with the upper sides of the plates 7, the rails in question being effectively braced by the angular bracing flanges 7^b which are formed integrally with the plates 7 and which contact snugly with the upper sides of the outer base flanges of the rails 3 and with the outer sides of said rails. The rail 1 rests partially upon the inner base flanges of the rails 3 and partially upon the upper side of the plates 7 flush with the upper sides of said base flanges, said rail 1 being held in this position by additional angular bracing flanges 8 which are formed integrally with the base plates 7 and which snugly contact with the inner side of said rail.

Due to the fact that the beveled surfaces

2
at the opposite ends of the rail 1 contact with the outwardly deflected ends of the rails 3, shifting of said rail 1 within the chairs is prevented, whereas the rails 3 are 5 allowed to slide freely toward each other upon expansion and to recede one from the other when contraction takes place. It is to be understood that the adjacent ends of the rails 3 are not positively bent outwardly, 10 but that they are merely sprung outwardly into contact with the outer sides of the rail 1, it being therefore evident that they will be swung still farther outwardly upon expansion, while they will straighten when 15 contraction takes place. Thus it will be seen that the inner sides of the rails 3 will aline at all times with the inner sides of the rail 1. Needless to say, this effect could not be obtained were the rails 3 positively bent. 20 In constructing a railway, the expansion compensating means above described are disposed at suitably spaced intervals throughout the length of both rails as indicated in diagram in Fig. 4. In this figure T designates the track which is composed of the usual rails secured rigidly together at J for stretches approximately a mile or a half mile long. At the ends of such stretches, 25 however, the expansion compensating means designated at E is disposed, it being thus evident that the track is divided into a plurality of independently movable units each of which is capable of expanding and contracting the necessary amount without any 30 danger whatsoever of buckling the rails or producing other injurious effects. Particular emphasis is laid upon the fact that when constructing a railway as described, the ends of the rails may abut closely as indicated in 35 Fig. 4 and may be secured together in such a manner as to prevent them from receding from each other, this being highly expedient since no gaps will then prevail at the joints. By the elimination of such gaps, 40 pounding of the car wheels in traveling over the railway is prevented, thus not only decreasing the sound usually caused by the passage of a train over the track but preventing the ends of the several rails from 45 becoming rounded as often occurs. Emphasis is also laid upon the fact that at the several points E, pounding is likewise prevented since the upper edges of the rails 1

lie flush with the rails 3 and the car wheels run gradually from one to the other, there 55 being no fixed point at which the wheels leave one rail and roll upon the other.

In addition to the preceding description and explanation, it may be well to state that the expansion compensating devices would 60 be particularly valuable when placed in the vicinity of diamond track crossings to prevent their being forced out of alinement by contraction or expansion of adjoining rails, as much trouble is now encountered in keep- 65 ing such crossings in proper shape.

From the foregoing description, taken in connection with the accompanying drawings, it will be evident that although very simple and inexpensive construction has 70 been provided for the attainment of the desired end, the invention will be highly efficient in operation and will fulfil a long felt need.

We claim:—

75 In combination, a plurality of alined anchored base plates having alined depressions in their upper sides of the width and depth of the base of a rail, a pair of spaced alined rails having their bases disposed slidably in the depressions with their innermost base flanges flush with the tops of the base plates, and having their adjacent ends sprung outwardly, angular bracing flanges formed integrally with the base plates and contact- 80 ing snugly with the outer sides of the rails, a third rail resting partially on the inner base flanges of the pair of rails and partially on the upper sides of the base plates flush with said base flanges, said third rail having 85 its end portions beveled to vanishing thicknesses at its ends proper with the bevels disposed in contact with the inner sides of the pair of rails, and additional angular bracing flanges formed integrally with the 90 base plates at points spaced from the depressions and contacting closely with the inner side of the third rail.

95 In testimony whereof we have hereunto set our hands in presence of two subscribing 100 witnesses.

JOHN MOORE.
RICHARD THORNTON.
